UNITED STATES PATENT OFFICE.

JOSEPH C. FAUST, OF DETROIT, MICHIGAN, ASSIGNOR TO PACKARD MOTOR CAR COMPANY, OF DETROIT, MICHIGAN, A CORPORATION OF MICHIGAN.

DESIGN FOR A BORDER OR SIMILAR DEVICE.

48,931.

Specification for Design.

Patented Apr. 25, 1916.

Application filed January 26, 1916. Serial No. 74,511. Term of patent 3½ years.

To all whom it may concern:

Be it known that I, JOSEPH C. FAUST, a citizen of the United States, residing at Detroit, in the county of Wayne and State of Michigan, have invented a new, original, and ornamental Design for a Border or Similar Device, of which the following is a specification, reference being had to the accompanying drawing, forming a part thereof.

The figure is a plan view of a border or similar device, embodying my design.

I claim:

The ornamental design for a border or similar device, as shown.

JOSEPH C. FAUST.
